CLAIM

The ornamental design for a top for a bathtub, as shown and described.

DESCRIPTION

FIG. 1 is a top plan view of a top for a bathtub showing my new design;

FIG. 2 is a perspective view thereof;

FIG. 3 is a cross sectional view taken on line 3—3 of FIG. 1;

FIG. 4 is a cross sectional view taken on line 4—4 of FIG. 1; and

FIG. 5 is a cross sectional view taken on line 5—5 of FIG. 1.

The broken line representation of a bathtub in FIGS. 1, 3, 4 and 5 is for purposes of illustration only.

FIG.1

FIG.2
